MICROMETER HEAD SPACE GAUGE

Leroy A. Woodward, Dickinson, N. Dak.

Application February 20, 1948, Serial No. 9,817

1 Claim. (Cl. 33—163)

1

My invention relates to gauges for measuring the head space of firearms, and more particularly to gauges of the micrometer type which are adapted to be inserted into the firing chamber of a firearm to correctly and accurately gauge the distance from the forward shoulder of such chamber to the closure for the rear end of the chamber.

In the manufacture of firearms, particularly rifles using fixed ammunition, it is necessary that the longitudinal dimensions of the firing chamber be extremely accurate, whereby the fixed ammunition will have the snug fit in such chamber with the rear end of the cartridge snugly abutting the forward face of the closure for the firing chamber which usually comprises a bolt. Thus, if the firing chamber is too long, too much head space is provided which comprises a space between the rear end of the cartridge and the face of the bolt which makes for the creation of dangerous pressures when the cartridge is fired. On the contrary, when the firing chamber is too short, the cartridge will not extend into it sufficiently, whereby the bolt either will not close or will not close completely. Consequently, it is of great interest to the manufacturer or gunsmith that the longitudinal dimension of the firing chamber be extremely accurately gauged, whereby the head space is proper for the ammunition for which the gun is designed.

With the foregoing in view, it is an object of my invention to provide an improved head space gauge.

A further object of the invention is to provide an improved head space gauge in the form of an interior micrometer which is insertable in the firing chamber of a firearm to measure the longitudinal dimensions thereof.

A further object is to provide in a head space gauge, such as that last described, means for locking the beam and the sleeve of the gauge together in a pre-set relation to each other.

Other objects and advantages reside in the particular construction of the device according to the invention, combination and arrangement of the several parts thereof, and will be readily understood by those skilled in the art upon reference to the attached drawing in connection with the following specification, wherein the invention is shown, described and claimed.

In the drawing:

Figure 1 is an elevation of a preferred form of the invention;

Figure 2 is a view like Figure 1, but showing a

2

portion of the outer sleeve in longitudinal vertical section;

Figure 3 is an end view looking from the right of Figure 1;

5 Figure 4 is a transverse vertical section taken substantially on the plane of the line 4—4 of Figure 2;

Figure 5 is an end elevation of a locking device looking from the left of Figure 6;

10 Figure 6 is a longitudinal vertical section through the locking device of Figure 5;

Figure 7 is a longitudinal vertical section through the butt end of a firearm showing the gauge according to the invention in use.

15 Referring specifically to the drawing, wherein like reference characters have been used throughout the several views to designate like parts, and referring more specifically to Figure 7, 10 designates generally the rear end of a barrel for a firearm which includes the usual bore 11 which merges with shoulders 12 into a firing chamber 13 at the rear end. The firing chamber 13 is normally closed at the rear by a movable closure 14, such as a bolt. Any suitable cartridge, not shown, having a shell case complementary to the shape of the firing chamber 13 is adapted to be positioned in the firing chamber 13 and secured therein by a bolt 14 for firing.

The gauge according to the invention comprises 20 a sleeve generally indicated by 15 which comprises a reduced central section 16 and enlarged end sections 18 and 19. The diametric dimensions of the enlarged sections 18 and 19 are such as to be substantially complementary to the interior of the firing chamber 13. The front section 18 merges into an inwardly-directed substantially frusto-conical shoulder 17 which is complementary to the shoulder 12 of the firing chamber. The reduced central section 16 may be provided with knurling 20 to provide a grip thereon. Obviously, the reduced central section 16 is not adapted to come in contact with the walls of the firing chamber 13, whereby to permit the knurling or stamping of markings on the central section 16. The rear enlarged section 19 may be inscribed with a suitable zero marker 21.

25 The sleeve 15 is formed with an interior bore 22 which extends rearwardly from the forward end thereof. The bore 22 is unthreaded and the forward end is outwardly flared to provide a substantially frusto-conical recess 23 which faces forwardly of the front end of the sleeve. Rearwardly, the bore 22 merges into an enlarged and threaded counter-bore 24 which in turn, in the 30 50 region of the enlarged rear section 19, merges

into a still further enlarged and unthreaded counter-bore 25.

A beam 26 is concentrically disposed within the sleeve 15. The beam 26 comprises a graduated rear end section 27 which is formed with a suitable zero graduation 28 and plus and minus graduations 29 and 30, Figure 2. The rear end of the section 27 extends outwardly of the second counter-bore 25 and is formed to provide the measuring head 31. The forward portion of the section 27 is slidably into and out of the counter-bore 25 in axial directions. A measuring thread section 32 of the beam 26 extends forwardly of the graduated section 27 and is threadedly received in the interiorly-threaded-counter-bore 24 of the sleeve. A cylindrical forward extension 33 of the beam is slidably received in the bore 22 of the sleeve and includes a terminal portion 34, a part of which at least extends outwardly or forwardly of the forward end of the sleeve 15. A lock nut 35 is threaded on the threaded terminal portion 34 of the beam and comprises an interiorly threaded sleeve member having a substantially frusto-conical rear end 36 which is formed with a plurality of radially-directed slots 37. The frusto-conical rear end 36 is adapted to be substantially complementary to the frusto-conical recess 23 in the forward end of the sleeve 15. The outer periphery of the nut 35 may be knurled or otherwise formed to provide a gripping surface. Such surface is best indicated at 38, in Figure 1.

In operation, the gauge according to the invention is inserted into a firing chamber 13 of a firearm, Figure 7, with the zero indicia or calibrations 21 and 28 of the sleeve and beam aligned. The bolt or closure 14 for the firing chamber is now closed. Assuming that the firing chamber 13 involved is too short, the bolt will either refuse to close entirely or will close only with a substantially great effort. This indicates that the firing chamber is too short, as the gauge when set with the zero indicia aligned is of the correct length to correspond to the cartridge designed for use in the particular gun. It should be mentioned at this time that prior to inserting the gauge into the firing chamber initially, the sleeve and beam are locked in the zero-indicating position by means of the lock nut 35 which is screwed down so that the spring end formed by the slots 37 is forced into locking and wedging engagement with the recess 23 of the sleeve and the threads of the threaded portion 34 of the beam. Upon the determination that the firing chamber 13 is too short, as aforesaid, the gauge is removed from the firing chamber, and the beam 26 is screwed in a direction to shorten the length of the same and register one of the minus graduations 29 of the beam with the zero indicator 21 of the sleeve. The lock nut 35 is once more tightened to lock the parts together and the gauge is reinserted in the firing chamber and the bolt is again closed. Assuming that the bolt now works freely, the setting of the gauge is noted, the lock nut is loosened, and the gauge is reset at an intermediate point between the last reading and the zero settings. Once more the gauge is inserted into the firing chamber, and the bolt closed. Assuming now that the bolt again works too tightly, the setting is once more noted and the new set-

ting of the gauge is made until the proper and accurate measurement of the longitudinal dimensions of the firing chamber is accomplished. The gauge will then indicate in the example described the amount by which the firing chamber 13 must be enlarged by boring away of the shoulder 12 thereof to insure proper head space between the rear of the cartridge and the forward face of the bolt 14. Obviously, when the initial test of the firing chamber indicates that the same is too long, the procedure is reversed until there has been determined the amount by which the firing chamber must be shortened by sawing off the rear end of the barrel 10.

By providing means for locking the moving parts of the gauge together during a measuring operation, extremely great accuracy is obtained and there is no danger of inaccurate readings caused by relative rotation of the parts during the opening and closing of the bolt and/or in the insertion or removal of the gauge from the chamber. Wear of the gauge parts is readily compensated for by setting the same to a position where it correctly designates the correct size of a desired firing chamber and then remarking the sleeve part 19 with a new zero setting 21 in alignment with the zero calibration 28 of the beam.

Thus, while I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

In a head space micrometer for measuring the distance from the internally shouldered forward end of a firing chamber to the forward end of a closed breech closure, including an internally threaded sleeve substantially complementary to said chamber and having front and rear ends, a beam having external threads at an intermediate portion thereof, said beam being threaded in said sleeve and having front and rear ends extending axially outwardly of both ends thereof, and a head formed on said rear end of said beam for engagement with said closure, the improvement comprising other screw threads formed on said front end of said beam, a lock nut threadedly and adjustably engaged with said last named threads, said sleeve including a forward end formed with a forwardly-directed frusto-conical recess axially thereof, said lock nut including a rear end formed with a rearwardly-directed frusto-conical sleeve engaging end, and said sleeve engaging end of said nut being wedgingly seatable in said recess, whereby to lock said beam and sleeve in pre-set relation to each other.

LEROY A. WOODWARD.
